CLOTHESPIN

Daniel W. Hilderbrant, Farmersville, Calif.

Application March 3, 1938, Serial No. 193,764

2 Claims. (Cl. 24—139)

This invention relates to a clothespin.

It is aimed to provide a novel and more efficient construction capable of manufacture from a single strand of metallic wire, which will be more securely anchored to the clothesline and in which the movement of the movable leg is entirely within the width of the article.

The more specific objects and advantages will become apparent from a consideration of the description following taken in connection with accompanying drawing illustrating an operative embodiment.

In said drawing:

Figure 1 is a view of the improved clothespin in side elevation;

Figure 2 is a view similar to Figure 1 but showing the movable leg in released position;

Figure 3 is an edge elevation of the clothespin, and

Figure 4 is a fragmentary perspective view showing the outer end of the movable leg and adjacent parts.

Referring specifically to the drawing wherein like reference characters designate like or similar parts, the clothespin is preferably made from a single strand of metallic wire which is formed into one or more coils 10 having substantially parallel, spaced apart legs 11 and 12 extending from the coil.

Leg or arm 11 has a tine 13 extending laterally therefrom having a terminal jaw 14 returned toward the legs, and then returned at a portion 15 away from the legs, thus forming a bifurcated hook, having the bifurcation or slot as at 16. The terminal of the portion 15 is coiled one or more times at 17 about the tine 13.

The resilient action of the leg 12 urges it from the position of Figure 2 to that of Figure 1 where it is partly entered in the bifurcation 16. The free end of leg 12 is coiled one or more times as at 18 about the tine 13, to provide an eyelet which is slidable thereon. Normally the eyelet 18 abuts the coil 17.

In the use of the device, leg 12 may be retracted

from the position of Figure 1 to that of Figure 2 enabling the hook 14 to be engaged over a clothesline, whereupon the leg 12 is released and its resilient action will force it away from the leg 11 until the eyelet 18 abuts coil 17 and the leg 12 is partly within the bifurcation 16. The clothes may be hung on the line and secured in place by engagement of the hook 14 thereover or they may be suspended from the coil 10 or in any other desired manner.

Various changes may be restored to provided they fall within the spirit and scope of the invention.

I claim as my invention:

1. A clothespin of the class described comprising a resilient strand, said strand consisting of a coil, legs extending in the same general direction from the coil, one of the legs having a tine, said tine adjacent its free end having a loop providing a hook, the free end of the loop being terminally coiled about the tine, said loop being returned upon itself to provide substantially parallel strands forming a bifurcation and substantially parallel strands outwardly of the first mentioned strands, and said movable leg being normally engaged with the second mentioned coil and disposed in the bifurcation.

2. A clothespin of the class described comprising a resilient strand, said strand consisting of a coil, legs extending in the same general direction from the coil, one of the legs having a tine, said tine adjacent its free end having a loop providing a hook, the free end of the loop being terminally coiled about the tine, said loop being returned upon itself to provide substantially parallel strands forming a bifurcation and substantially parallel strands outwardly of the first mentioned strands, said movable leg being normally engaged with the second mentioned coil and disposed in the bifurcation, and an eyelet at the free end of the movable leg slidable on the tine and engageable with the second mentioned coil.

DANIEL W. HILDERBRANT.
